OIL SAVING SEPARATOR FOR COOLING SYSTEMS

Arthur G. Wood, Geronimo, Okla.

Application May 20, 1943, Serial No. 487,774

6 Claims. (Cl. 183—75)

This invention relates to a system or apparatus whereby the lubricating oil in an internal combustion engine will be maintained relatively cool, and that fraction usually lost through evaporation will be saved and used.

More specifically, I aim to provide for the introduction of air with circulating oil returned to a crank case, and means to separate or remove the oil from the air as it leaves the crank case, and which feeds such air to the carburetor for use in the fuel system.

In addition, I aim to provide a novel construction of separator for air and oil or other material.

Various additional objects and advantages will become apparent from a consideration of the description following taken in connection with accompanying drawings illustrating an operative embodiment.

In said drawings:

Figure 1 is a central longitudinal sectional view through the separator;

Figure 2 is a cross-sectional view taken on the line 4—4 of Figure 1;

Figure 3 is a cross-sectional view taken on the line 5—5 of Figure 1;

Figure 4 is a cross-sectional view taken on the line 6—6 of Figure 1;

Figure 5 is a cross-sectional view taken on the line 7—7 of Figure 1;

Figure 6 is a cross-sectional view taken on the line 8—8 of Figure 1.

Numeral 20 denotes a separator having a cylindrical or other casing 25' provided with a removable cover 26 telescoped in the upper portion thereof with the joints sealed by means of removable gaskets at 27 and 28.

Gasket 27 is supported on a transverse wall or partition 29 within the casing 25 spaced above another transverse partition or wall 30. Mounted concentrically of the cylinder 25 with its ends spaced from the ends of the casing 25 is a shell or auxiliary cylinder 31. An annular chamber 32 thus is provided within the cylinder by the parts 25, 29, 30, and 31, with which the conduits 19 communicate adjacent the top and supply thereto the mixture of air and oil vapor passing from the engine.

The mixture from chamber 32 will pass downwardly therefrom through openings or ports 33 in the partition 30, arranged relatively close to the auxiliary cylinder or shell 31, when it will be deflected inwardly toward such shell by a depending, inwardly tapering skirt 34 below said partition 30, being directed into an inclined collector 35 whose inner edge is fastened to the shell 31. The mixture then passes through a series of depending tubes 35' fastened to the shell 31 and communicating with the collector 35 adjacent the base of the latter, the same thus dis-

charging the mixture adjacent the base of the cylinder 25.

A plurality of bell conduits 36, open at the bottom, communicate adjacent closed tops with ports or openings 37 in the wall of the auxiliary cylinder 31, such bell hoods 36 being of U shape in cross-section, as best shown in Figures 6 and 7, and at their longitudinal edges being soldered or welded to the periphery of the auxiliary cylinder 31. Such bell hoods 36 extend downwardly through and below the collector 35, the latter being welded or soldered to the exterior of the bell hoods 36, so that the oil cannot escape but will pass downwardly through the tubes 35'.

Between the base of the cylinder 25 and the lower ends of the bell hoods 36 is a perforated wall or partition 37', and at the bases of the bell hoods 36 a deflector 38 preferably is provided, which is marginally in spaced relation to the wall of the cylinder 25 to permit passage of air downwardly between the same. Thus air or mixture which does not pass into the collector 35 will pass downwardly around the periphery of the deflector 38 and thence upwardly through the bell hoods 36 and ports 37 into the interior of the auxiliary cylinder 31.

Any vapor which passes downwardly through the tubes 35', also will join that air or vapor which ascends through the bell hoods 36.

A partition or wall 39 is located within the auxiliary cylinder 31 below the openings 37, and adjacent the partition 39 outlet ports 40 are provided in a centrally located tube or conduit 41 arranged to drain oil adjacent the base of the cylinder 25 through ports 42 formed in an enlargement 43.

The auxiliary cylinder 31 will discharge the air and any vapor therein into an upper chamber 44 provided within the cover or closure 26. An inverted conical collector 45 is located in chamber 44, extending from the central tube 41, and the latter having receiving openings or ports 46 therein adjacent the base of collector 45 so that oil may drain therefrom into the tube 41. The upper end of the latter preferably is closed as by means of a cork or any equivalent 47, to avoid any effect of suction incidental to operation. The air from the collector 45 will enter the lower end of outlet pipe 22 whose lower end extends into the receptacle, and which pipe extends through and is soldered or welded to the closure 26.

To facilitate the separation of oil from the air, I preferably provide steel wool or any equivalent at different locations, and especially at 48 in the collector 35, at 49 on the perforated plate 37', at 50 on the partition 39, and at 51 in the collector 45.

Conduits or drain pipes 52 extend from the partition 29 through the partition 30 to convey

oil from the upper chamber 44 into the collector 35.

As a result of the invention, the intaken air after performing its cooling function passes from the separator through the pipe 22 into the carburetor for use in the fuel system, while oil vapors which normally would be lost are condensed and returned into the oil pan and used.

Various changes may be resorted to provided that they fall within the spirit and scope of the invention.

I claim as my invention:

1. A separator of the class described comprising a casing, partitions therein, a cylinder within the casing and coacting with the partitions to provide a receiving chamber, a partition in said cylinder, a collector on said cylinder below the first-mentioned partitions to receive the mixture through the lowermost of said first-mentioned partitions, means for drainage of condensate from the collector, hood means about the cylinder to receive the mixture below the collector, ports in the cylinder for entry of the mixture from the hood means into the same above the partition of the cylinder, said casing providing means to receive mixture from the cylinder, said casing having an upper chamber, a collector in said upper chamber, a discharge pipe leading from the second-mentioned collector for drainage of oil therefrom, and a pipe to discharge air communicating with the second-mentioned collector.

2. A separator of the class described comprising a casing, partitions therein, a cylinder within the casing and coacting with the partitions to provide a receiving chamber, a partition in said cylinder, a collector on said cylinder below the first-mentioned partitions to receive the mixture through the lowermost of said first-mentioned partitions, means for drainage of condensate from the collector, hood means about the cylinder to receive the mixture below the collector, ports in the cylinder for entry of the mixture from the hood means into the same above the partition of the cylinder, said casing providing means to receive mixture from the cylinder, said casing having an upper chamber, a collector in said upper chamber, a discharge pipe leading from the second-mentioned collector for drainage of oil therefrom, and a pipe to discharge air communicating with the second-mentioned collector, the discharge tube being closed at the top and within the discharge pipe, said discharge tube passing through said partition in the cylinder and adjacent same communicating with the cylinder.

3. A separator of the class described comprising a casing, partitions therein, a cylinder within the casing and coacting with the partitions to provide a receiving chamber, a partition in said cylinder, a collector on said cylinder below the first-mentioned partitions to receive the mixture through the lowermost of said first-mentioned partitions, means for drainage of condensate from the collector, hood means about the cylinder to receive the mixture below the collector, ports in the cylinder for entry of the mixture from the hood means into the same above the partition of the cylinder, said casing providing means to receive mixture from the cylinder, said casing having an upper chamber, a collector in said upper chamber, a discharge pipe leading from the second-mentioned collector for drainage of oil therefrom, and a pipe to discharge air com-

municating with the second-mentioned collector, said hood means being open at the bottom and extending through the first-mentioned collector.

4. A separator of the class described comprising a casing, partitions therein, a cylinder within the casing and coacting with the partitions to provide a receiving chamber, a partition in said cylinder, a collector on said cylinder below the first-mentioned partitions to receive the mixture through the lowermost of said first-mentioned partitions, tubes fastened to the cylinder for drainage of condensate from the collector, hood means about the cylinder to receive the mixture below the collector, ports in the cylinder for entry of the mixture from the hood means into the same above the partition of the cylinder, said casing providing means to receive mixture from the cylinder, said casing having an upper chamber, a collector in said upper chamber, a discharge pipe leading from the second-mentioned collector for drainage of oil therefrom, and a pipe to discharge air communicating with the second-mentioned collector, said hood means being open at the bottom and extending through the first-mentioned collector.

5. A separator of the class described comprising a casing, partitions therein, a cylinder within the casing and coacting with the partitions to provide a receiving chamber, a partition in said cylinder, a collector on said cylinder below the first-mentioned partitions to receive the mixture through the lowermost of said first-mentioned partitions, means for drainage of condensate from the collector, hood means about the cylinder to receive the mixture below the collector, ports in the cylinder for entry of the mixture from the hood means into the same above the partition of the cylinder, said casing providing means to receive mixture from the cylinder, said casing having an upper chamber, a collector in said upper chamber, a discharge pipe leading from the second-mentioned collector for drainage of oil therefrom, and a pipe to discharge air communicating with the second-mentioned collector, a skirt extending downwardly and inwardly below the first-mentioned partitions to direct mixture into the first-mentioned collector.

6. A separator of the class described comprising a casing, partitions therein, a cylinder within the casing and coacting with the partitions to provide a receiving chamber, a partition in said cylinder, a collector on said cylinder below the first-mentioned partitions to receive the mixture through the lowermost of said first-mentioned partitions, means for drainage of condensate from the collector, hood means about the cylinder to receive the mixture below the collector, ports in the cylinder for entry of the mixture from the hood means into the same above the partition of the cylinder, said casing providing means to receive mixture from the cylinder, said casing having an upper chamber, a collector in said upper chamber, a discharge pipe leading from the second-mentioned collector for drainage of oil therefrom, and a pipe to discharge air communicating with the second-mentioned collector, a skirt extending downwardly and inwardly below the first-mentioned partitions to direct mixture into the first-mentioned collector, and drain pipes leading from the upper chamber to the first-mentioned collector through the first-mentioned partitions.

ARTHUR G. WOOD.
